US0D1038046S

(12) **United States Design Patent** (10) Patent No.: **US D1,038,046 S**
(45) Date of Patent: ** Aug. 6, 2024

- (54) **REMOTE CONTROL APPARATUS
WIRELESS**
- (71) Applicant: **SOMFY ACTIVITES SA**, Cluses (FR)
- (72) Inventors: **Mathieu Prevoteau**, Meythet (FR);
Jonathan Tordjman, Sèvres (FR)
- (73) Assignee: **SOMFY ACTIVITES SA**, Cluses (FR)

(**) Term: **15 Years**

(21) Appl. No.: **35/517,651**

(22) Filed: **Jun. 8, 2023**

(80) **Hague Agreement Data**

Int. Filing Date: **Jun. 8, 2023**

Int. Reg. No.: **DM/229741**

Int. Reg. Date: **Jun. 8, 2023**

Int. Reg. Pub. Date: **Jun. 30, 2023**

(30) **Foreign Application Priority Data**

Dec. 21, 2022 (WO) WIPO126701

(51) **LOC (14) Cl.** **14-03**

(52) **U.S. Cl.**

USPC **D13/168**; D14/218

(57) **CLAIM**

The ornamental design for a remote control apparatus wireless, as shown and described.

DESCRIPTION

The patent or application file contains at least one drawing executed in color. Copies of this patent or patent application publication with color drawing(s) will be provided by the Office upon request and payment of the necessary fee.

1. Remote control apparatus wireless

1.1 : Front perspective

1.2 : Front

1.3 : Back

1.4 : Right

1.5 : Left

1.6 : Top

1.7 : Bottom

The broken lines in the drawings depicting the surface indicia "my" is for illustrative purpose only and form no part of the claimed design. The two circular features and the arrow shown in reproduction 1.3 are depicted in yellow and form no part of the claimed design.
